UNITED STATES PATENT OFFICE.

ROBERT WALTON WIEDERWAX, OF ATLANTIC CITY, NEW JERSEY, ASSIGNOR TO GEIST MANUFACTURING COMPANY, OF ATLANTIC CITY, NEW JERSEY, A CORPORATION OF DELAWARE.

APPARATUS FOR BURNING BRICK.

Application filed October 3, 1924. Serial No. 741,461.

This invention relates to an apparatus for burning bricks and more particularly to an apparatus for carrying out and controlling the "water smoking" step in brick making, 5 and then finishing the burning process whereby improved and more uniform bricks may be made in less time than is possible by the present methods.

It is the usual practice to carry out the 10 manufacture of bricks in two distinct steps, namely, the "water smoking" step and the burning step. These two steps in the manufacture of bricks require several days for their completion and result in bricks which 15 are not uniform as to color and many of the bricks are cracked and chipped due largely to the inefficiency of the present methods of practising the "water smoking" step.

It is the present practise to initially place 20 the plastic bricks in the kiln and burn in the fire openings of the kiln pieces of wood saturated in oil, the wood occasionally being replenished to slowly heat the bricks and drive off a large portion of the water 25 contained therein after which the usual fires are built to greatly raise the temperature of the bricks to complete the burning or baking operation. The initial step whereby the excess water is driven off is 30 commonly known as "water smoking" and is a critical and slowly accomplished step in brick making, ordinarily requiring about two days for its completion and necessitating the constant attendance of about four 35 operators when the process is carried out in a kiln of average size. It has been found exceedingly difficult to maintain evenly a correct temperature during the "water smoking" of the bricks. The temperature must 40 be sufficiently high to evaporate a large portion of the water content of the bricks, but not sufficiently high to generate steam, since such a temperature has been found to cause chipping and splitting of the bricks due to 45 small explosions of steam generated within the bricks.

In the practise of the present method of "water smoking" it has been found that the 50 combustion of the fuel employed is not complete and the bricks often become greatly discolored during the "water smoking" operation; particularly adjacent the arches, due to the condensation of unburned oil, sulfur deposits, etc.

An important object of the present invention is to provide an apparatus whereby the temperature of the bricks may be readily controlled during the "water smoking" operation so that the excess water efficiently may be driven off without raising the temperature to such a point as to cause splitting and cracking of the bricks. 55

A further object of the invention is to provide an apparatus for carrying out the "water smoking" operation in such a manner 60 as to prevent discoloration of the bricks thus resulting in the manufacture of bricks of improved quality and more uniform appearance. 65

A still further object of the invention contemplates the completion of the "water smoking" operation in a much shorter period of time than is now necessary with the attendance of only one or two operators. 70

The present method consists generally in 75 providing a preheating tunnel provided with damper controlled outlet pipes leading into the ash pits of a kiln, a highly efficient type of oil burner being mounted adjacent the inlet opening of the tunnel for heating 80 the air therein. The inlet opening of the tunnel is preferably considerably larger than the burner employed so that the aspirating action of the burner results in introducing into the tunnel large quantities of 85 air which becomes heated by the burner after which it is introduced through the outlet pipes into the ash pits of the kiln. The products of combustion from the burner and the heated air mixed therewith flow upwardly through the grates commonly employed, into the arches formed when placing the bricks in the kiln, from whence they circulate between the individual bricks to 90 raise the temperature thereof to drive off a large portion of the water. The burner easily may be controlled to provide air and products of combustion of the proper temperature and the dampers may be regulated 95 to feed equal amounts of the heated air and products of combustion into each of the ash pits. 100

The "water smoking" operation according to the present invention usually may be completed in the average kiln in about ten hours 105 after which the burning or baking operation may be started.

In carrying out the last step of the method

2
I prefer to arrange an oil burner in each of the fire box openings of the kiln, the burners employed preferably being of a type wherein combustion of the oil is complete and wherein the individual burners may be controlled to maintain the bricks at a proper temperature. The baking burners are not in operation during the "water smoking" step of the method but are lighted immediately after the completion of the "water smoking" step and are adapted to maintain the bricks at a relatively high temperature during the baking operation. By the use of the "water smoking" method above outlined the proper percentage of water may be driven off from the bricks and the latter properly "set" whereby the burning operation may be completed and it has been found that the completed bricks present a uniform appearance without discoloration of any kind and the bricks are of improved quality.

In the drawings I have shown several organizations of apparatus elements for carrying out the method. In this showing,

25 Figure 1 is a perspective view of a kiln showing the invention applied,

Figure 2 is a fragmentary perspective view of one of the heating tunnels,

30 Figure 3 is a detail perspective view of a portion of the kiln taken through one of the grates and showing the bricks in elevation therein,

35 Figure 4 is a transverse sectional view through one of the walls of the kiln taken through one of the fire box openings, and,

Figure 5 is a horizontal sectional view of a circular kiln showing the heating tunnel applied.

40 Referring to the drawings the numeral 10 designates a "Dutch" type of kiln having opposite walls 11 provided with fire box openings 12 and ash pits 13. The spaces between the walls 11 are open at the ends as shown and a canopy (not shown) is employed for covering the kiln in the usual manner. As shown in Figures 3 and 4, a floor 14 is provided within the kiln and grates 15 are arranged within the floor as shown. The grates 15 correspond in number and arrangement to the fire box openings 12. The kiln just described is preferably of the usual type of "Dutch" kiln and forms no part of the present invention.

45 Referring to Figures 1 and 4, the numeral 55 16 designates a plurality of oil burners, each mounted in one of the fire box openings 12, as clearly shown. The burners 16 are preferably of the type shown in my prior Patent No. 1,460,631, granted July 3, 1923, since such burner has been found particularly adapted for use in connection with the present method. Each burner 16 employs pre-heating retorts (not shown) for the oil and steam, the oil being supplied through a feed pipe 17 and the steam through a feed pipe

18, as shown in Figure 4. Steam is fed to the burner nozzle through a pipe 19 controlled by a valve 20 while the oil is fed to the nozzle by a pipe 21 controlled by a valve 22. The burners are preferably mounted in the manner shown in Figure 4 with their inner ends projecting a short distance into the fire box openings.

70 The numeral 23 designates as a whole a preheating tunnel preferably formed of brick and substantially U-shaped as clearly shown in Figure 2. The tunnel is provided with an interior unrestricted passage 24 closed at the outer ends to prevent the escape of heated air and products of combustion from the tunnel. An inlet branch 25 is provided for the tunnel having a relatively large inlet opening 26 in which is mounted a burner 27 preferably of the type previously described. It will be obvious that the burner only partially fills the inlet opening 26 and when the burner is in operation its aspirating action results in injecting a large quantity of air into the tunnel through the opening 26 as will be obvious. As shown in 80 Figure 1, the opposite sides of the tunnel 23 are arranged against the outer faces of the walls 11 of the kiln and a pipe 28 leads from the passage 24 into each of the ash pits 13. Dampers 29 are arranged in the 85 pipes 28 and are adapted to be controlled by handles 30 arranged above the tunnel as clearly shown.

90 In Figure 5 of the drawings I have shown a circular tunnel 31 applied to a circular 100 kiln 32 of the usual construction. The tunnel 31 is provided with an inlet branch 33 in the outer end of which is mounted a burner 34 preferably similar to the burner 27 previously described. Pipes 35 are arranged 105 within the ash pit openings of the kiln to permit heated air and products of combustion to flow into the ash pits from the tunnel 31. Each fire box opening of the kiln 32 is 110 provided with a burner 36 also preferably 115 of the type previously described.

120 The bricks to be "water smoked" and "burned" are placed in the kiln in the usual manner as shown in Figure 3. The bricks 37 are formed to the proper shape while in 115 a plastic condition in the usual manner and are arranged to provide arches 38 over each of the grates 15, tie rows 39 being provided in the usual manner to prevent the arches from collapsing.

125 In carrying out the present method the plastic bricks are arranged in the kiln in the usual manner as illustrated in Figure 3, an arch being provided over each of the grates 15 throughout both sides of the kiln as will be obvious. The burner 27 is then started and products of combustion are injected into the passage 24 as will be obvious. The aspirating action of the burner 27 causes large quantities of air to be drawn 130

into the passage 24 as long as the burner 27 is in operation. The dampers 29 are then regulated by their handles 30 to feed substantially equal quantities of heated air and products of combustion into each of the ash pits 13. It will be obvious that the dampers nearest the burner 27 will be closed more than those toward the outer ends of the tunnel in order that the desired result just described may be accomplished. It has been found that by proper operation of the burner 27 and dampers 29 a correct temperature of the bricks easily may be maintained whereby the "water smoking" step of the method may be efficiently carried out. The burner 27 is maintained in operation approximately ten hours during which time the desired percentage of water will be evaporated from the bricks. Complete combustion of the oil from the burner 27 is assisted by the aspirated air passing into the tunnel and the air forms the principal heating medium for "water smoking" the bricks. This fact permits the "water smoking" operation to be carried out without depositing unburned oil, sulfur, etc., on the bricks adjacent the arches and discoloration of the bricks is effectually prevented. By maintaining an even temperature in the bricks beneath the boiling point of the water therein, splitting and chipping of the bricks during the initial step of the method also is effectually prevented and the operation is carried out in much less time than is required by the method now used.

After the "water smoking" operation has been completed the burners 16 are started to raise the temperature of the bricks to the proper point for carrying out the burning or baking operation. The aspirating action of the burners 16 also results in introducing large quantities of heated air into the spaces between the bricks so that the latter are properly heated to complete the operation without depositing any foreign matter on the bricks so as to cause discoloration. The "water smoking" operation having been previously carried out in an efficient manner the burning or baking step of the method may be completed without danger of chipping or splitting the bricks. The most critical step in the method, however, is the "water smoking" step and by the method just described this step may be carried out in a very efficient manner and the burners require little attention during the completion of the step of the method.

The same method previously described is

also followed when the apparatus is employed in connection with a circular kiln as shown in Figure 5. The burner 34 is operated in the same manner for completing the "water smoking" operation after which the burners 36 are operated to complete the burning or baking step of the method.

While I have described in detail the preferred practice of my method and forms of apparatus by which it may be carried out, it is to be understood that the details of procedure of the method and the forms of apparatus described may be widely varied without departing from the spirit of the invention or the scope of the subjoined claims.

Having described my invention, I claim:

1. An apparatus of the character described comprising a tunnel arranged in proximity to a kiln and provided with a series of spaced pipes projecting thereinto, said tunnel being provided with a relatively large inlet opening, and an oil burner arranged in and spaced from the sides of said opening, said burner being adapted to project a flame into said tunnel and to continuously introduce air thereinto by aspiration of the flame.

2. An apparatus of the character described comprising a substantially U-shaped tunnel having its arms arranged against the walls of the kiln opposite the ash pit openings therein, pipes carried by the arms of the tunnel and projecting into the ash pits, dampers arranged in said pipes, said tunnel being provided with a relatively large inlet opening, an oil burner adapted to project a continuous flame into said tunnel through said opening, and to continuously introduce air into said tunnel by the aspiration of the flame, and an oil burner arranged in each fire box opening of the kiln.

3. An apparatus of the character described comprising a tunnel formed of refractory material having portions arranged in proximity to a kiln and provided with a series of spaced pipes projecting thereinto, said tunnel being provided with a relatively large inlet opening remote from said pipes, and an oil burner arranged in and spaced from the sides of said opening, said burner being adapted to project a flame into said tunnel and to continuously introduce air thereinto by aspiration of the flame.

In testimony whereof I affix my signature.

ROBERT WALTON WIEDERWAX.
